UNITED STATES PATENT OFFICE.

FRANK R. FILTER, OF WATERTOWN, MASSACHUSETTS, ASSIGNOR TO STANDARD OIL COMPANY OF NEW YORK, OF NEW YORK, N. Y., A CORPORATION OF NEW YORK.

TANK WAGON.

Application filed June 2, 1921. Serial No. 474,488.

To all whom it may concern:

Be it known that I, FRANK R. FILTER, a citizen of the United States, residing at Watertown, in the county of Middlesex and 5 State of Massachusetts, have invented certain new and useful Improvements in Tank Wagons, of which the following is a specification.

This invention relates to vehicles of that 10 class commonly called tank wagons, and it has for its object to improve the construction thereof.

Tank wagons of the kind referred to are used in transporting and dispensing liquids 15 such as gasoline, kerosene, etc., the body of the vehicle consisting of a large sheet iron tank at the rear end of which is provided one or more, usually several, faucets through 20 which the contents of the tank body can be drawn off into measures in making deliveries to customers. These faucets are connected with one or more outlets at the bottom of the tank body by pipes and it is customary to provide valves within the body by means of 25 which the said outlets may be closed to prevent accidental escape, or leakage at the faucets. These valves are manually operated through means which extends upwardly through the top of the tank to the exterior of 30 the latter, and it is intended, and usually made a strict rule, that said valves be in open positions only while a delivery is being made to a customer, and each be left in its closed 35 position while the vehicle is traveling from one place of delivery to another. In order to do this, however, it is necessary for the person in charge to climb up onto the vehicle both immediately before and immediately 40 after making a delivery in order to reach the valve operating means, which is objectionable, particularly to the person in charge. Therefore, it is common practice for the latter, when starting upon his route, to disregard this rule and open the valves, and to 45 leave them in that condition until he has completed all of the deliveries throughout the route covered by him. Frequently, upon occasions of this kind, it has happened that one or more of the faucets have been accidentally or maliciously opened thus permitting the discharge of gasoline from the tank onto the ground. It has also happened that a 50 tank wagon containing gasoline and traveling through a city street with its valves open has been struck in the rear by another ve-

hicle with the result that the faucets of the tank wagon were broken off, permitting the contents of the latter to discharge onto the roadway, where it caught fire, destroyed the wagon and endangered other property as 60 well as lives. The main object of my invention is to obviate the objectionable features pointed out above and to provide simple, reliable and efficient means for ensuring the closing of the valves after each delivery so as 65 to prevent the discharge of the contents of the wagon if the faucets are accidentally or maliciously opened, or broken off through collision with another vehicle.

To these ends I have provided a tank 70 wagon with the peculiar features of construction and combination of parts set forth in the following description, the novel and distinguishing features of said structure being particularly pointed out and defined in 75 the claims at the close thereof.

In the accompanying drawings:

Figure 1 is an elevation of the rear end of the body of a tank wagon having applied thereto an embodiment of my invention. 80

Figure 2 is a partial section on line 2—2 of Figure 1.

Figure 3 is a side view partly in section of the rear end portion of the wagon.

Figure 4 is a section on line 4—4 of Figure 3. 85

Figure 5 is a section on line 5—5 of Figure 4.

Wagons or vehicles of the class to which my invention relates comprise a tank body 1, 90 made from sheet metal, constructed at its rear end with a compartment 2 within which are stored the measures or other vessels used in making deliveries to customers, said compartment being separated from the liquid holding compartment 3 by a partition or wall 4, and commonly being termed a bucket-box. The compartment 2 is normally closed as usual, by a door 5 connected by hinges 6 with body 1, spring latches 7 on body 1 serving to lock said door 5 in closed position. Just below the compartment 2 are the usual faucets 9 connected by pipes 10 with the liquid holding compartment 3. Upon arriving at a place of delivery the driver depresses latches 7, opens door 5, removes from compartment 2 the measures he is to use, draws off the required amount of liquid at faucets 9, and delivers the same to the customer, replaces the measures within compartment 2, 100 105 110

and, after closing the door 5, moves on to the next place of delivery. As will be clear it is necessary for the driver to open door 5 in order to obtain the measures and it is also necessary for him to close the door 5 after replacing the measures in order to avoid loss of the same while traveling over the road.

In carrying out my invention I provide, within compartment 2, a bracket 11, riveted, or otherwise secured, to the inner side of the rear wall 12 of body 1 just above the door 5. This bracket 11 is made with a pair of downwardly projecting arms which embrace the hub of a bell crank lever 16 pivoted at 17 to said arms. One arm 18 of bell crank 16 is provided upon opposite sides of its free end with studs 19 that co-operate with a yoke 20, the latter being fastened by rivets, or otherwise, to the inner side of the door 5. When the door 5 is in its closed position the two arms 21, 21 of yoke 20 straddle the lower portion of the bracket 11, but when the door is swung outwardly and upwardly on its hinges 6 the two arms 21 swing downwardly and outwardly in a direction to engage the studs 19 of bell crank lever 16. The other arm 22 of bell crank 16 is connected through a pin and slot connection 23 with the lower end of a connecting rod 24 whose upper end is provided with a yoke 25 pivotally connected with an arm 26. The lower portion of the connecting rod 24 is within the compartment 2 and said rod extends upwardly through an opening 27 provided in the body 1 to the arm 26 which is upon the exterior of the body. The arm 26 is fastened on the rear end portion of a rock shaft 28 which extends horizontally lengthwise of the tank body 1. The rear end of rock shaft 28 is journaled in a bracket 29 secured to the top of tank body 1, while forward of said bracket 29 the rockshaft is journaled in another bracket 35, see Figs. 3 and 4. Adjacent bracket 35 the shaft 28 is provided with an arm 36 having a pin and slot connection 37 with one arm of a lever 38 fulcrumed at 39 upon bracket 35. The other arm 40 of lever 38 is bifurcated and straddles a collar 41 fast upon the upper end of a link 42, said collar being made with an annular groove into which project studs 43 on arm 40.

It will now be clear that when the door is swung from its closed position shown in Figure 2 into its open position shown in Figure 3 the two arms 21 of yoke 20 engage the studs 19 and act through bell crank 16, link 24, arm 26, rock shaft 28, arm 36 and lever 38, to move link 42 upwardly. This link 42 extends downwardly from lever 38, through a stuffing box 44, into compartment 3, of tank body 1, to near the bottom of the latter where its lower end is pivotally connected by a pin 45, Fig. 5, with a valve engaging lever 46. Lever 46 is fulcrumed at 47 upon an arm 48 forming part of a valve body 49 that

occupies a hole provided in the bottom of the tank to which latter said body may be brazed, welded, or otherwise secured. The stuffing box 44 is made with a radially extending annular flange 50 to which the bracket 35 is fastened by means of a screw 51, the body portion of said stuffing box being exteriorly threaded and screwed into a threaded opening in the top of tank 1.

Near its free end the lever 46 is made with a hole through which extends the threaded stem 52 of the shut-off valve 53, the latter being adapted to close downwardly onto a seat 54 provided upon body 49. Nuts 59, 60, upon said threaded stem are engaged by the lever 46 for the actuation of the valve. Valve 53 controls an outlet port 55 formed through body 49 and connected by a delivery pipe 56 with a manifold 57 to which the faucets 9 are connected, each by a pipe 10.

To the valve engaging lever 46 is fastened one end of a leaf spring 58 that extends under fulcrum pin 47 with its free end resting upon the bottom of tank 1 so that said spring is under a normal initial stress which holds shut-off valve 53 on its seat. The spring 58 is permitted to perform this function by reason of the pin and slot connection at 23, and lost motion or play at the various joints in the train of connections.

It will thus be clear that when the door 5 is swung from its open position shown in Figure 3 to its closed position shown in Figure 2, the lever 46 and spring 58 act to lower the valve 53 onto its seat, the said valve 53 being thus automatically opened when the door 5 is swung into its open position and automatically closed when the door 5 is swung into its closed position.

As means for supporting the door 5 in its open position I have herein provided a pair of collapsible struts 30, 30, each consisting of two sections pivotally connected at their abutting inner ends by a knuckle joint 31 and at their outer ends said sections are pivotally connected as at 32 and 33 to the door 5 and body 1, respectively. When the struts 30 occupy their extended positions they rigidly support the door 5 in its open position, and it will be clear that by pushing inwardly upon the two struts the door 5 can be unlocked and closed downwardly, the two struts folding up within the compartment 2 as shown in Figs. 1 and 2.

My invention provides simple and reliable means for insuring the closing of shut-off valve 53 after each delivery, so that accidental or malicious opening of a faucet, or injury to a faucet or its pipes, cannot effect the discharge of the contents of the tank 1. Also, in the case of leaky faucets, wastage is prevented. An advantage of the construction above described is that the shut-off valve is operated by the driver through means within his reach from

his position upon the ground at the rear of the vehicle. Another advantage is that the shut-off valve is automatically opened when the compartment door 5 is opened and is 5 automatically closed when said compartment door is closed. Thus the driver, or person in charge, is relieved of the duty of either opening or closing the valve. Naturally the driver will return the measures 10 to the compartment 2 and close the door 5 upon completing a delivery, and will, of necessity, open the door to secure his measures when about to make a delivery. It follows therefore that the shut-off valve will 15 always be open when deliveries are being made and will always be closed while the vehicle is traveling over the road. Preferably I arrange the bell crank lever 16 so that should, for any reason, the spring 58 20 fail to close the valve 53 when the door 5 is closed, then said door will act through said lever 16 and parts connected with the latter to positively return the valve 53 to its closed position. The shut-off valve of 25 the construction above described being automatically closed, none of the contents of the tank 1 can leak out if either the faucet or the delivery line itself is damaged. It sometimes happens that while "on the road" a 30 faucet starts to leak because of the seat of the faucet valve becoming worn. These seats are made of textile fabric composition and occasionally give out, so that if the shut-off valve is open there is leakage at the faucet. This leakage cannot occur with the

construction above described. Where the shut-off valve operating means is located on top of the tank the same is operated infrequently, so that when it is necessary to close said valve as in the case of damage to 40 the faucet or pipe line, said means is sometimes found to stick, therefore becoming "frozen." Constant use of the valve operating means of my improved construction keeps the same in perfect working condition. 45

What I claim is:

1. The combination with a tank having an outlet, a box having a door, and a valve adapted to close said outlet, of operating connections between said door and said valve 50 including a lever in said box actuated by the door in closing to bring about the closing of the valve, and a bracket moving with the door engaging with said lever in the opening movement of the door to open the valve. 55

2. The combination with a tank having an outlet, a box having a door, and a valve adapted to close said outlet, of operating connections between said door and said valve including a lever in said box actuated by the 60 door in closing to bring about the closing of the valve, and a bracket moving with the door engaging with said lever in the opening movement of the door to open the valve, and means to maintain the door in open 65 position.

In testimony whereof I have affixed my signature.

FRANK R. FILTER.
